TREATMENT OF HYDROCARBON MATERIALS

Maryan P. Matuszak, Bartlesville, Okla., assignor
to Phillips Petroleum Company, a corporation of
Delaware

Application May 26, 1941, Serial No. 395,280

4 Claims. (Cl. 196—13)

This invention relates to the treatment of hydrocarbon materials and more particularly to the treatment of hydrocarbon materials containing relatively unsaturated hydrocarbons under such conditions as to remove substantially all of the unsaturated hydrocarbons contained therein. It relates particularly to the removal of aliphatic unsaturated compounds from relatively low-boiling hydrocarbon fractions.

Heretofore, hydrocarbon materials containing unsaturated hydrocarbons have been treated with sulfuric acid in order to remove said unsaturated hydrocarbons. In many cases this treatment is only partially successful due apparently to the oxidizing effect of the acid on the unsaturated constituents of the oil. This is especially true when concentrated sulfuric acid is used for the treatment. The oxidizing effect is of such a nature that substances are produced in the main body of the hydrocarbon material which bring about an unstable condition in the material with respect to color and odor.

Furthermore, it has been proposed to associate sulfuric acid with boric acid, phosphoric acid, nitric acid or acetic acid to remove certain undesirable material from mixtures of hydrocarbons. Also, undesirable material has been removed from mixtures of hydrocarbons by treating the mixtures with either nitric acid, acetic acid, phosphoric acid or maleic anhydride alone or mixtures of hydrochloric acid and ores of certain metals. In many of these instances the material so removed comprises diolefins, objectionable color-forming, odor-forming, sulfur and/or analogous constituents objectionable for inclusion in motor fuel and does not include mono-olefins.

I have now found that a hydrocarbon material can be freed of substantially all its content of unsaturated hydrocarbons, particularly when the unsaturated hydrocarbons are aliphatic and cyclic, nonaromatic unsaturated hydrocarbons and their derivatives, such as olefins, diolefins, cycloolefins, and derivatives such as styrene, by treating these hydrocarbon materials with substantial amounts of hydrofluoric acid. I have also found that, in connection with such treatments, hydrofluoric acid which tends to remain in the treated hydrocarbon material can be removed by a physical treatment more particularly to be described.

An object of this invention is to remove unsaturated hydrocarbons from certain hydrocarbon materials.

Another object of this invention is to remove unsaturated hydrocarbons from normally gaseous and/or normally liquid hydrocarbons by the use of a treating material and thereby produce a substantially saturated hydrocarbon product free from the treating material and free from unsaturated hydrocarbons.

A further object is to provide a process for treating hydrocarbon materials whereby oxidizable, polymerizable, gum-forming, and color-forming constituents are removed.

Further objects and advantages of this invention will become apparent from the accompanying disclosure and discussion.

These objects may be accomplished in accordance with my invention by treating hydrocarbon materials normally gaseous and/or normally liquid and in either gaseous or liquid phase with hydrofluoric acid at ordinary temperatures and in sufficient amount to remove substantially all unsaturated hydrocarbons. As a modification this treating operation may be cooperatively combined in my invention with a separation step wherein hydrofluoric acid is removed from the product in a novel manner, involving distillation.

The hydrocarbon materials and the hydrofluoric acid are preferably in the liquid phase although the application of my process is not limited to treating only in liquid phase, as in some instances, especially with a C₄ hydrocarbon fraction or similar low-boiling fraction, the hydrocarbon material may be partially or entirely in the vapor phase. Although I prefer to employ substantially anhydrous hydrofluoric acid or hydrogen fluoride as treating material in my process, at times I may advantageously treat hydrocarbon material containing unsaturated hydrocarbons with acid containing small amounts of diluent material, especially water, so that the concentration of the hydrofluoric acid in the treating material may range between about 90 and 100 per cent acid by weight.

The amount of hydrofluoric acid originally used should be sufficient to form a distinct and appreciable liquid phase containing a major proportion of hydrofluoric acid under the conditions of treatment and, preferably, is several times this amount. The amount will vary with the nature of the hydrocarbon material treated, and particularly with the content of relatively unsaturated hydrocarbons. The amount of hydrofluoric acid for treating generally should not be less than that required to produce a substantially saturated hydrocarbon material. An amount of hydrofluoric acid equal to or several

times greater than the hydrocarbon material to be treated may be set as approximately the maximum that may need to be used. However, an amount between 10 and 50 per cent by volume of the hydrocarbon material will generally be found satisfactory.

Hydrocarbon materials consisting predominantly or entirely of unsaturated hydrocarbons are generally not satisfactorily treated by the present process, although, if for some reason it appears desirable to treat such materials with hydrofluoric acid, for example, to remove part or all of the unsaturated hydrocarbons, this treatment is entirely within the spirit of the invention. Furthermore, when unsaturated hydrocarbons are the predominant hydrocarbon materials comprising a mixture containing non-hydrocarbon constituents substantially inert to and insoluble in hydrofluoric acid under the prevailing conditions, my invention will find particular application for removing substantially all of the unsaturated hydrocarbons therefrom.

The mutual solubility of liquid hydrocarbons and of liquid hydrofluoric acid increases appreciably with increase in temperature, and this will need to be taken into consideration in establishing the treating conditions in any particular case.

Treatment with hydrofluoric acid of hydrocarbon material containing unsaturated hydrocarbons may, for certain individual cases be conducted, however, at temperatures ranging from about -100 to about 300° F. although in most cases I prefer to operate between about 0 and 150° F. The pressure should be sufficient to insure proper flow through the apparatus, and when liquid phase operation is desired should be such to insure this at the temperature of operation.

In the treatment of normally liquid hydrocarbon material, such as motor fuels, kerosenes, fuel oils, Diesel oils, and lubricating oils, and the like, containing unsaturated hydrocarbons, a relatively low-boiling liquefied paraffin, such as propane or a butane, preferably normal butane, or a mixture of relatively low-boiling liquefied paraffins, can be added to the normally liquid hydrocarbon material before, during, or after contacting said material with hydrofluoric acid. This low-boiling hydrocarbon material so added aids in subsequent removal of residual hydrogen fluoride which will remain dissolved in the hydrocarbon phase after physical separation of the major part of the hydrofluoric acid phase.

In a preferred manner of operating, a normally liquid hydrocarbon material is treated with hydrofluoric acid, an acid phase separated from a hydrocarbon phase containing normally liquid hydrocarbons and dissolved hydrofluoric acid, after which a low-boiling liquefied paraffin or mixture of such paraffins is added to said hydrocarbon phase. This is often preferably to having a low-boiling paraffin hydrocarbon present when an acid phase is also present in the treatment of normally liquid hydrocarbon. In either case the hydrocarbon phase is fractionally distilled to remove a low-boiling fraction in which the distilled low-boiling paraffin hydrocarbon carries with it, as a part of the low-boiling mixture, hydrofluoric acid which formerly had been dissolved in the normally liquid hydrocarbon phase. Such low-boiling hydrocarbons form minimum-boiling azeotropic mixtures with hydrofluoric acid, and with the proper conditions the overhead fraction will be such an azeotropic mixture. How-

ever, in actual plant operations such close control will often not be feasible, although the process will have taken advantage of this characteristic. Such treatment effects removal of hydrofluoric acid from the normally liquid hydrocarbon phase

5 without the loss of this material that would occur if the removal were made by water-washing, alkali-washing, or the like and without the same increase in temperature that would be necessary 10 for removal of the acid by simple fractional distillation. However, simple fractional distillation of the dissolved hydrofluoric acid from the treated liquid hydrocarbon material, without prior addition of a relatively low-boiling paraffin, may be practiced. The acid removed by either type of fractional distillation is suitable 15 for re-use in the treatment of additional hydrocarbon material.

The invention will now be described in connection 20 with the accompanying drawing, which forms a part of this specification and illustrates diagrammatically an arrangement of apparatus for carrying out my process, the description serving to exemplify the invention.

25 A charge stock comprising a hydrocarbon material which contains undesired unsaturated hydrocarbons is admitted through conduit 10 controlled by valve 11 to a contacting chamber 12 wherein it is thoroughly contacted with liquid hydrofluoric acid. The hydrocarbon material enters chamber 12 preferably in the liquid phase and the pressure and temperature maintained in chamber 12 are such that the constituents are substantially in the liquid phase at all times, 30 although it is well within the spirit of my invention to contact a low-boiling hydrocarbon material in the gas or vapor phase with hydrofluoric acid in the liquid phase. Hydrofluoric acid is admitted to the apparatus through conduit 13 35 controlled by valve 14 to chamber 12 and in the liquid phase is dispersed in chamber 12. The contacting of the acid and hydrocarbon material may be batchwise or continuous, and may be concurrent effected by any of several well-known 40 mixing devices, such as efficient stirring mechanisms, turbulence chambers, etc., but it is preferably continuous and countercurrent, so that fresh acid comes in contact with hydrocarbon material that has already lost most of its content 45 of relatively unsaturated hydrocarbons, in a manner known to the art. Sufficient hydrofluoric acid is admitted to chamber 12 so that under preferred conditions of operation a liquid phase containing a major portion of hydrofluoric acid 50 and a minor portion of hydrocarbon and another liquid phase containing a major portion of hydrocarbons and a minor portion of hydrofluoric acid are present therein. Ordinary temperatures or 55 slightly below or above ordinary temperatures such as between 0 and 150° F. can be maintained in chamber 12.

60 A hydrofluoric acid phase containing material removed from the hydrocarbon fraction charged through conduit 10 is passed from contacting chamber 12 through conduit 15 controlled by valve 16 to a separating means 20. A purified concentrated hydrofluoric acid is separated from undesired material and passed through conduit 23 and valve 24 to conduit 13 for re-use in the system. Such separation may be accomplished primarily by means of fractional distillation in 65 many cases.

70 Any desired part or all of this hydrofluoric acid stream may be removed from the system through conduit 25 controlled by valve 26 which connects

with conduit 23. Undesired organic material from which this hydrofluoric acid has been separated is removed from separating means 20 through a conduit 21 controlled by a valve 22 and is discharged from the system.

A purified more or less completely saturated hydrocarbon stream which will generally be in a liquid phase and containing a minor amount of dissolved hydrofluoric acid is removed from contacting chamber 12 through conduit 30 and may be passed directly through valves 31 and 32 to a fractionating means 33. In fractionating means 33 the desired hydrocarbon fraction is purified from the small amount of hydrofluoric acid contained therein and is recovered as a product of the process through conduit 34 controlled by a valve 35. A low-boiling fraction containing hydrofluoric acid is removed through conduit 36 and may be returned to the contacting chamber for further use in the process through valves 37 and 38 to conduit 10. If desired it may be introduced at an intermediate point of the contacting chamber as by being passed through conduit 40 and valve 41 from conduit 36. Any portion or all of the material passing through conduit 36 may be removed from the system through conduit 42 controlled by valve 39.

When the hydrocarbon material treated in the process is normally liquid and contains substantially no or only small amounts of low-boiling hydrocarbons such as propane, butane, or pentane, it is found desirable to conduct the distillation in fractionating means 33 in the presence of an amount of such a low-boiling hydrocarbon as will form an azeotropic mixture with the hydrofluoric acid and thereby promote its separation from the purified hydrocarbon product. An amount of low-boiling hydrocarbon sufficient to have this effect and preferably an amount of such low-boiling hydrocarbon somewhat in excess of the exact amount required to form such an azeotropic mixture should be introduced into the fractionating means. Such a low-boiling paraffin can be introduced to the system through conduit 46 controlled by a valve 45, may be passed directly through a valve 43 to conduit 30 or may be introduced at an intermediate point in fractionating means 33 as through conduit 46 controlled by a valve 41. With this method of operation a low-boiling fraction removed through conduit 36 will contain a substantial proportion or all of such low-boiling paraffin hydrocarbons which may be recycled within the system as described. In some instances it may be desired to effect a separation between the hydrocarbon and hydrofluoric acid constituents from the material passing through conduit 36 in which case any part or all of this stream may be passed through conduit 62 controlled by valve 63 to separating means 66. In separation means 66 a hydrofluoric acid fraction, separated in a desired manner, may be removed therefrom through conduit 68 controlled by a valve 67 and returned to the system by being passed through conduit 13. Any desired part of this stream may be removed from the system through conduit 70 controlled by valve 71. A suitable low-boiling paraffin fraction may be removed from separating means 66 and returned to the system through conduit 64 controlled by a valve 65 which leads to conduit 44. At times it may be found that the presence of a low-boiling paraffin material in the contacting chamber 12 will aid the separation of hydrofluoric acid and hydrocarbon phases in this con-

tacting chamber in which case a part of the material passing through conduit 44 may be passed through conduit 48 controlled by a valve 49 to conduit 36 and the contacting chamber 12.

5 In many instances the purification carried out in contacting chamber 12 will be at a temperature which is more or less elevated, and a preliminary separation of hydrofluoric acid dissolved in the hydrocarbon stream passing through conduit 30 may be effected by cooling this stream to atmospheric or subatmospheric temperature. In this case any desired portion of the stream may be passed from conduit 30 through conduit 50 controlled by a valve 51, cooled in cooler 52 to a desired separation temperature, preferably between 10 and 50° F., and passed through conduit 53 to a separator 55. In separator 55 a separation will take place at this lower temperature between a liquid hydrofluoric acid phase and a hydrocarbon phase. The hydrofluoric acid phase may be passed from separator 55 through conduit 56 controlled by a valve 57 to conduit 15 for subsequent treatment in separating means 20 as described. If desired, any part or all of this stream may be discharged from the system from conduit 58 controlled by a valve 59. Separator 55 will also be used when the contacting chamber is operated in a concurrent manner rather than the countercurrent system specifically shown or when batch operation is employed. The 10 hydrocarbon phase is passed from separator 55 through conduit 60 controlled by a valve 61 back to conduit 30 for subsequent treatment in the system as herein discussed.

While the particular separation system carried 15 out with fractional distillation in the presence of a low-boiling paraffin forms a distinct modification of the invention, I do not wish to be restricted to this specific modification in all cases, and may effect a separation of the hydrofluoric acid dissolved in the hydrocarbon stream passing through conduit 30 in any manner which may be convenient or known to the art as by washing this material with water or an alkaline aqueous solution. Such other separation may be carried out in separating means 66 in which case the purified hydrocarbon material is passed from conduit 30 through conduit 72 controlled by a valve 73 to separating means 66 and a purified hydrocarbon product is recovered through conduit 74 controlled by a valve 75.

My invention will more generally be carried out 20 in connection with the removal of unsaturated hydrocarbons from low-boiling hydrocarbon fractions such as gasoline or kerosene or the like, although as discussed it may also be applied to fractions which are higher-boiling or lower-boiling than such stocks. The purification in contacting chamber 12 will preferably be carried out in a liquid phase although when low-boiling stocks such as the C₄ fraction from a cracking still or the like is being treated it may at times be found desirable to have the hydrocarbon material in vapor phase. In connection with the purification of a liquid stock together with a separation of the dissolved hydrofluoric acid from the purified material in fractionating means 33, an initial amount of low-boiling paraffins such as normal butane may be added through conduit 44 at the start of the process after which this low-boiling paraffin 25 may be recycled within the system as previously discussed with further additions of low-boiling paraffin being made only for the purpose of compensating for unavoidable losses. When the hydrocarbon material charged through conduit 10 30 contains such a low-boiling paraffin it may be un-

necessary to add additional material through conduit 44 and after a steady state of separation has been reached with suitable recycle with the low-boiling paraffin removed through conduit 36, the purified hydrocarbon product recovered through conduit 34 will contain substantially the same amount as was contained in the material charged through conduit 10.

It will, of course, be appreciated that the drawing is diagrammatic and does not show in detail many pieces of equipment such as pumps, heat exchangers, heating coils, cooling coils, reflux lines, and the like which are well known to the art and which normally form a part of the various pieces of equipment shown diagrammatically. When employing fractionating means 33 this can be a single fractionating column with ordinary bubble plates or other internal construction known to the art with suitable means for providing a liquid reflux. Although it will generally not be necessary, fractionating means 33 may comprise two or more fractional distillation columns in some particular instances. The exact equipment to be installed and conditions for its operation for any particular use of my invention may be readily ascertained by one skilled in the art in the light of the accompanying disclosure and discussion.

In order to more clearly illustrate my invention and the desirable results obtained thereby, the following examples are given. The conditions given therein exemplify the invention, but are not necessarily to be used to limit the invention.

Example I

An alkylate obtained by the sulfuric acid alkylation of isobutane with a refinery cut containing a substantial proportion of gaseous olefins, mainly normal butylenes, is treated with about a fifth of its own volume of liquid hydrofluoric acid. The treated alkylate, after separation and withdrawal of the acid phase, is washed acid-free with water. The olefin content of the alkylate decreases from an original value of about 1.5 per cent to so small a value that it cannot be measured by titration of a sample with a dilute solution of bromine in carbon tetrachloride.

Example II

A motor fuel comprising chiefly octanes but containing 0.8 to 1.0 per cent of octenes that escaped hydrogenation in a preceding hydrogenation step is mixed with about a tenth of its own volume of liquefied normal butane and about the same amount of liquid hydrofluoric acid. After a thorough mixing, the mixture is cooled to about 40° F.; the acid is allowed to separate and is withdrawn. The hydrocarbon mixture is fractionally distilled to remove the added butane and the dissolved hydrofluoric acid. The residual motor fuel is free from hydrofluoric acid and is free from olefinic hydrocarbons.

The acid phase which is separated and withdrawn from a hydrocarbon phase is subjected to fractional distillation whereupon hydrofluoric acid is separated from unsaturated hydrocarbons. The hydrofluoric acid is recovered and in a continuous process is mixed with incoming hydrocarbon charge stock.

What is claimed is:

1. A process of treating a hydrocarbon material containing normally liquid hydrocarbons and unsaturated hydrocarbons, which comprises contacting such hydrocarbon material with liquid hydrofluoric acid in a contacting chamber and in suffi-

cient amount to produce a liquid phase containing a major portion of the hydrofluoric acid, passing a mixture of hydrocarbon material and hydrofluoric acid to a first separating means and separating therein said liquid phase from a phase containing normally liquid substantially saturated hydrocarbons and dissolved hydrofluoric acid, passing at least a portion of the liquid phase containing a major portion of the hydrofluoric acid to a second separating means, recovering hydrofluoric acid from said second separating means and returning at least a part of said acid to the contacting chamber, admixing with the phase containing normally liquid substantially saturated hydrocarbons and dissolved hydrofluoric acid a relatively low-boiling paraffinic material, passing this admixture to a fractional distillation means and separating therefrom a low-boiling fraction containing low-boiling paraffinic hydrocarbon material and hydrofluoric acid, separating also a fraction containing saturated normally liquid hydrocarbon material substantially free from unsaturated hydrocarbons and hydrofluoric acid and removing the saturated normally liquid hydrocarbon material from the process.

2. A process of treating a hydrocarbon material containing normally liquid hydrocarbons and unsaturated hydrocarbons, which comprises admixing such hydrocarbon material with substantially anhydrous hydrofluoric acid in a contacting chamber, passing a resulting hydrocarbon-containing mixture to a separating means, removing therefrom a liquid phase containing normally liquid substantially saturated hydrocarbons and dissolved hydrofluoric acid, admixing with the liquid phase a relatively low-boiling paraffinic material, passing the liquid phase and relatively low-boiling paraffinic material to a fractional distillation means, separating from said distillation means a low-boiling fraction containing at least a portion of the low-boiling paraffinic material and substantially all of the dissolved hydrofluoric acid, passing said fraction to a treating means from which hydrofluoric acid is removed, circulating said hydrofluoric acid to the contacting chamber, separating also from the fractional distillation means a higher boiling fraction containing saturated normally liquid hydrocarbons substantially free from unsaturated hydrocarbons and hydrofluoric acid, and removing said higher boiling fraction from the process.

3. A process of treating a hydrocarbon material containing normally liquid hydrocarbons and unsaturated hydrocarbons, which comprises admixing such hydrocarbon material with substantially anhydrous hydrofluoric acid in a contacting chamber, passing a resulting hydrocarbon containing mixture to a separating means, removing therefrom a liquid phase containing normally liquid substantially saturated hydrocarbons and dissolved hydrofluoric acid, admixing with the liquid phase a relatively low-boiling paraffinic material in an amount at least sufficient to form an azeotropic mixture with said dissolved hydrofluoric acid, passing the liquid phase and relatively low-boiling paraffinic material to a fractional distillation means, separating from said distillation means a low-boiling fraction containing at least a portion of the low-boiling paraffinic material and substantially all of the dissolved hydrofluoric acid, passing said fraction to a treating means from which hydrofluoric acid is removed, and circulating said hydrofluoric acid to the contacting chamber, separating also from the fractional distillation means a higher boiling fraction containing

saturated normally liquid hydrocarbons free from unsaturated hydrocarbons and hydrofluoric acid, and removing said higher boiling fraction from the process.

4. A process of treating a hydrocarbon material containing at least some unsaturated hydrocarbons, which comprises contacting the hydrocarbon material with liquid hydrofluoric acid in a contacting chamber and in sufficient amount to form a liquid phase containing a major portion of the hydrofluoric acid and a liquid phase containing a mixture of the hydrocarbon materials and the remaining hydrofluoric acid, passing said mixture of hydrocarbon material and remaining hydrofluoric acid to a first separating means, removing therefrom a liquid phase containing hydrofluoric acid and passing said phase along with the liquid phase containing a major portion of the hydrofluoric acid to a second separating means wherein hydrofluoric acid suitable for reuse in the treatment of additional hydrocarbon material is separated and returned to the contacting chamber; removing also from the first separating means a second phase containing substantially

saturated hydrocarbons and dissolved hydrofluoric acid, admixing with this second phase a relatively low boiling paraffinic material in an amount at least sufficient to form an azeotropic mixture with said dissolved hydrofluoric acid, passing this second phase with admixed low boiling paraffinic material to a fractional distillation means, separating therefrom a low boiling fraction containing at least a portion of the low boiling paraffinic material and substantially all of the dissolved hydrofluoric acid, passing said fraction to a treating means from which hydrofluoric acid is removed and circulating said hydrofluoric acid to the contacting chamber, and separating from the treating means the low boiling paraffinic material and recirculating this material to the fractional distillation means, and separating also from the treating means and from the fractional distillation means higher boiling fractions containing saturated normally liquid hydrocarbons free from unsaturated hydrocarbons and hydrofluoric acid, and removing said saturated hydrocarbon fractions from the process.

MARYAN P. MATUSZAK.
